COASTER

Joseph B. Richardson, Norfolk, Va.

Application November 30, 1948, Serial No. 149,882

Term of patent 14 years

(Cl. D44—10)

To all whom it may concern:

Be it known that I, Joseph B. Richardson, a citizen of the United States of America, residing at Norfolk, in the County of Norfolk and State of Virginia, have invented a new, original, and ornamental Design for a Coaster, of which the following is a specification, reference being had to the accompanying drawing, forming part thereof.

Fig. 1 is a plan view of a coaster, showing my new design.

Fig. 2 is a bottom plan view.

Fig. 3 is a sectional view taken on line 3—3 of Fig. 1.

I claim:

The ornamental design for a coaster, as shown.

JOSEPH B. RICHARDSON.
